UNITED STATES PATENT OFFICE.

MORIS M. BERGER, OF CLEVELAND HEIGHTS, OHIO.

PLUMBING-FIXTURE FOR BATH-TUBS.

1,290,702.

Specification of Letters Patent.

Patented Jan. 7, 1919.

Application filed March 26, 1918. Serial No. 224,851.

To all whom it may concern:

Be it known that I, MORIS M. BERGER, a citizen of the United States, residing at Cleveland Heights, in the county of Cuyahoga and State of Ohio, have invented a new and useful Plumbing-Fixture for Bath-Tubs, of which the following is a specification.

This invention relates to improvements in plumbing fixtures for bath-tubs, and pertains more especially to a combined water-supply and overflow fixture comprising a metal casting which is contoured as required to form two elbows arranged vertically and the one above the other and adapted to be applied to the outer side of the foot end wall of a bath-tub and has the lower elbow adapted to communicate at its upper end with the overflow-opening in said wall and 20 adapted to communicate at its lower end with a waste-pipe and has the upper elbow adapted to be placed in open relation at its upper end with a water-supply pipe or fixture and has the lower end of the upper elbow screw-threaded internally for receiving the correspondingly externally screw-threaded water-receiving end of a spout adapted to extend through said wall and to discharge into the tub.

30 One object of this invention is to produce a combined supply and overflow bath-tub plumbing fixture which can be manufactured with facility and is readily applied to and detachable from the tub.

35 Another object is to produce a fixture of the character indicated which is compact, simple and durable in construction, and not liable to get out of order.

Another object is to have the hereinbefore mentioned casting suitable for the reception, at a point between the passageways formed by the elbows, of a screw or bolt employed in the attachment to said casting of a strainer-forming plate applied to the inner side of the hereinbefore mentioned wall and to utilize the aforesaid spout in holding said plate in proper position and to utilize said spout in supporting said casting from said wall.

50 With these objects in view, and to attain any other object hereinafter appearing, this invention consists in certain features of construction, and combinations and relative arrangement of the parts, hereinafter described in this specification, pointed out in

the claims, and illustrated in the accompanying drawings.

In said drawings, Figure 1 is a sectional view of a portion of a bath-tub provided with a combined supply and overflow fixture embodying my invention and provided with a strainer connected to said fixture. Fig. 2 is a vertical section taken along the line 2—2, Fig. 1, looking inwardly. Fig. 3 is a vertical section taken along the line 3—3, Fig. 1, looking outwardly. Fig. 4 is an elevation taken along the line 4—4, Fig. 1.

Referring to said drawings, A indicates a portion of the foot end wall of a bath-tub, and said wall (see Figs. 1 and 5) is provided with an opening 5 at which water is adapted to overflow from the tub. The opening 5 extends laterally through the wall A, and said wall is provided above said opening with a hole 6 which is spaced from said opening and extends laterally through said wall. At the outer side of the wall A of the bath-tub and adjacent the hole 6 and overflow-opening 5 in said wall is applied a combined supply and overflow fixture embodying meritorious features of my invention and shown as comprising a body B which is in the form of a circular cast metal plate shown abutting at one face thereof against said side of said wall and extending around said overflow-opening and around the hole 6. Preferably the overflow-opening 5 is semi-circular and widest at the top thereof, as shown in dotted lines, Fig. 4. The body B has its lower portion provided with an outwardly and downwardly projecting tubular member 7 which is integral with said body and in the form of a vertically arranged elbow and (see Fig. 1) has its lower end-portion screw-threaded internally and adapted to be connected to a waste-pipe (not shown). The elbow or tubular member 7 forms a passageway 8 which extends endwise through said member, and is shown in Fig. 1 as communicating at the inner face of said body with the overflow-opening 5 and is employed in establishing communication between said opening and the aforesaid waste-pipe and in conducting off water from said opening. The elbow or tubular member 7 is gradually enlarged in width upwardly, as at 9, Figs. 3 and 4, toward the top thereof so as to permit the formation of a passageway 8 which

substantially corresponds in dimensions and form at its water-receiving end,—that is, at the inner face of the body B,—with the dimensions and form of the overflow-opening 5 and so as to permit said passageway to properly register at said end with said opening. The elbow or tubular member 7 is provided externally of the top of its inner and upper end-portion with a lug 10 which 10 is arranged centrally between the sides of said end-portion of said elbow or tubular member and is provided with a horizontally arranged screw-threaded hole 12 which extends from within said lug to the inner face 15 of the body B and is shown in line endwise (see Fig. 1) with a bolt-hole 13 formed in and extending laterally through the wall A of the bath-tub. The hole 12 is engaged by the correspondingly threaded shank of a 20 bolt C, and said shank extends from within said hole through the hole 13 in said wall and a suitable distance inwardly beyond the inner side of said wall and through a hole 14 formed in a concavo-convex plate D and 25 has a head 15 arranged at and abutting against the convex side of said plate. Said plate is circular and has an annular marginal flange 16 abutting against the inner side of the wall A of the bath-tub and is large 30 enough in dimensions to extend from below said overflow-opening to and above the hole 6 in said wall. The plate D has its lower portion,—that is, the portion thereof below the bolt C,—provided with slots d and therefore foraminated, and said slots are arranged opposite the overflow-opening 5, and hence the slotted or foraminated plate D forms a strainer. The bolt C not only participates in holding the strainer-forming plate 35 D in place but is seated in and supported from the wall A of the bath-tub and participates in supporting the plate or body B from said wall A.

The body B is provided above the lug 40 10 of the elbow or tubular member 7 of said body with an outwardly and upwardly projecting tubular member 17 which is formed therefore on the upper portion of and integral with said body and is in the 45 form of a vertically arranged elbow which has its upper and outer end-portion screw-threaded externally and is adapted to be connected at its upper end with a suitably valved water-supply pipe or fixture (not shown). The upper elbow or tubular member 17 has its lower and inner end-portion screw-threaded internally and engaged by the adjacent correspondingly externally screw-threaded outer end-portion of a spout- 50 forming tubular member E which extends from within the elbow or tubular member 17 through the hole 6 in the wall A of the bath-tub and into and through an opening 18 formed in the upper portion of the strainer-forming plate D and discharges 55 into the tub. The spout E is therefore detachably connected to the upper elbow or tubular member 17 of the body B and seated in and consequently supported from the end wall A of the bath-tub and serves as a 60 support for the casting forming said body and its elbows or projections 7 and 17 and also forms a seat for the upper portion of and thereby serves as a support for the strainer-forming plate D and prevents displacement of the strainer circumferentially of the bolt C. The spout E is in communication at its water-receiving end with the passageway 19 formed internally of the upper elbow or tubular member 17, and said 65 passageway extends to the upper extremity of said elbow or tubular member of said body and is adapted to receive water to be supplied to said spout.

The joint formed between the spout E 70 and the wall A of the bath-tub and the joint formed between the body B and the tub are rendered fluid-tight in any approved manner.

By the construction hereinbefore described it will be observed that the hereinbefore stated objects of my invention are 75 successfully attained.

What I claim is—

1. The combination, with a wall of a bath-tub, said wall having an overflow-opening extending laterally through the wall, of a combined supply and overflow fixture comprising two tubular elbows which are integral with each other and arranged vertically at the outer side of said wall and the one above the other, the upper elbow forming a passageway adapted to receive water at the upper end of said elbow and to be placed in communication with the interior of the tub, and the lower elbow forming a passageway arranged to conduct off water from the outer end of the aforesaid opening, and a tubular member threaded into the lower and inner end-portion of the upper elbow and communicating with the aforesaid passageway in said upper elbow and extending laterally through and supported from the aforesaid wall. 80
2. The combination, with a wall of a bath-tub, which wall has an overflow-opening extending laterally through the wall and enlarged in width toward the top thereof, said wall being provided above said opening with a circular hole extending laterally through the wall, and a cast-metal body arranged at the outer side of said wall and extending around said circular hole and around said overflow-opening and having a tubular member which projects outwardly and downwardly and communicates with said overflow-opening and is enlarged in width toward the top thereof, said body being provided above said tubular member with another tubular member which projects out. 85
